Primary Examiner — Karen S Acker*Assistant Examiner* — Wendy Arminio(74) *Attorney, Agent, or Firm* — Leason Ellis LLP(57) **CLAIM**

I claim the ornamental design for a covering for an architectural opening, as shown and described.

DESCRIPTION

FIG. 1 is a top-left isometric view of a covering for an architectural opening.

FIG. 2 is a front elevation view thereof.

FIG. 3 is a left side elevation view thereof.

FIG. 4 is a right side elevation view thereof.

FIG. 5 is a top plan view thereof.

FIG. 6 is a bottom plan view thereof; and,

FIG. 7 is a rear elevation view thereof.

The broken lines depict features of the covering for an architectural opening that form no part of the claimed design.
